UNITED STATES PATENT OFFICE.

SOLOMON M. GRAUMLICH, OF DUVALL STATION, OHIO.

FORCE-FEED FOR GRAIN-ELEVATORS.

SPECIFICATION forming part of Letters Patent No. 366,476, dated July 12, 1887.

Application filed March 23, 1887. Serial No. 232,063. (No model.)

To all whom it may concern:

Be it known that I, SOLOMON M. GRAUMLICH, a citizen of the United States, and a resident of Duvall Station, in the county of 5 Pickaway and State of Ohio, have invented certain new and useful Improvements in Force-Feeds; and I do hereby declare that the following is a full, clear, and exact description of the invention, which will enable others skilled in the art to which it appertains to make and use the same, reference being had to the accompanying drawings, which form a part of this specification, and in which—

Figure 1 is a side elevation of a feed-hopper, 15 in which my invention is mounted in its operative position, the side of the hopper being removed to better illustrate the arrangement of the several parts. Fig. 2 is a vertical sectional view taken on the plane indicated by 20 line $x-x$, Fig. 3; and Fig. 3 is a vertical sectional view taken on the plane indicated by line $y-y$, Fig. 2.

The same letters of reference indicate corresponding parts in all the figures.

25 My invention consists in an improved force-feed for the hoppers or "dumps" of grain-elevators, which will effectually prevent the mouth of the hopper from choking, and also prevent an arch from forming over the feed- 30 roller proper; and my invention will be hereinafter fully described and claimed.

Referring to the several parts by letter, A indicates a hopper of ordinary construction having the inwardly-sloping walls and the 35 discharge opening or mouth B at its lower end. Across and in this mouth B is mounted on a transverse shaft, C, the feed-roller D, which is formed on its sides with the longitudinal ribs D', for the purpose of feeding the grain down 40 through the mouth and preventing it from clogging the same, and on the outer projecting end of the roller-shaft C is secured a pulley, C', around which passes a suitable drive-belt, O, which rotates the feed-roller. At a suitable 45 distance above this feed-roller is secured within the hopper, to the side walls thereof, a transverse or cross beam, E, which is preferably arranged transversely across the feed-roller, as shown, and upon the central part of this 50 beam, immediately above the feed-roller, is secured a metal box or casting, F, which is preferably cast in two halves or sections, and

which has the central space, F', and the upper and lower vertical apertures or bearings, F²F². Through these bearings extends a perpendicular shaft, G, both the lower and upper ends of which are curved or bent over at nearly right angles, and each end of this shaft is also provided with two curved transverse arms, G'G', which upon the central part of this shaft, 60 which is inclosed within the metal box, is rigidly mounted a miter-wheel, H.

Through one side of the hopper, and also through a bearing in one side of the metal box F, passes a transverse shaft, I, which is provided at its inner end with a miter-wheel, I', which meshes with the miter-wheel on the central part of the perpendicular shaft G, while the outer end of this shaft I is provided with a pulley, I², around which passes a drive 70 band or belt, J, from the feed-roller shaft C, by which means the shaft I is rotated. That portion of the shaft I between the metal box F and the inner face or side of the wall of the hopper, through which it passes, is formed with 75 two square cranks, I³, for the purpose herein-after specified.

Through the opposite wall of the hopper to that through which the shaft I passes extends a second transverse shaft, K, the inner end of 80 which passes through a bearing in that side of the metal box F, and has rigidly secured on its inner extremity a miter-wheel, K', which meshes with the miter-wheel on the center of the perpendicular shaft G, and the central 85 part of this shaft K, between the metal box F and the side of the hopper, is formed with two square cranks, K', similar to those of the shaft I.

In the frame L, immediately below the mouth of the hopper, is journaled, in bearings, 90 a transverse shaft, M, around which passes the lower end of a suitable elevator-belt, the cups of which are thus carried immediately beneath the discharge-mouth of the hopper to receive the grain fed down through the same, 95 in the usual manner, and as this elevator-chain, with its cups, is of ordinary construction and forms no part of my present invention, I will not describe them in detail.

In operation the shaft of the feed-roller is 100 revolved through the drive-belt O from a suitable source of power, and it will be seen that the ribbed feed-roller will effectually force and feed the grain surrounding it down through

the mouth of the hopper into the cups of the elevator chain or belt. At the same time the transverse shaft I will be rotated through the drive-belt J from the feed-roller shaft, and as it is rotated the miter-wheel, on its inner end meshing with the miter-wheel secured on the central portion of the perpendicular feed-shaft G, will revolve the said perpendicular shaft, and the curved pointed upper and lower ends 5 of the said shaft, and also the curved transverse arms G' near its upper and lower end, will stir and agitate the grain and feed it down upon the feed-roller. At the same time the miter-wheel K² on the inner end of the other transverse shaft, K, meshing with the miter-wheel 10 on the center of the perpendicular shaft G; the said shaft K will be rotated in unison with the shaft I, and the projecting cranks of the 15 said two transverse shafts will operate in conjunction with the bent ends and curved transverse arms of the perpendicular shaft G to gently stir the grain in the hopper, and thus while feeding it regularly down upon the feed-roller will effectually prevent the grain from 20 forming an arch of compact grain above the feed-roller, which it would otherwise do.

From the foregoing description, taken in connection with the accompanying drawings, the construction, operation, and advantages 25 of my invention will be readily understood.

My improved force-feed apparatus is simple and strong in construction, and therefore not liable to break or get out of order in any manner, and is exceedingly effective in its operation, as it will be impossible for the grain to 30 pack into an arch above the feed-roller, and it will be fed evenly and smoothly down upon the feed-roller, and the ribbed feed-roller will operate to feed the grain down evenly and 35 steadily through the bottom of the hopper into the cups of the conveyer-belt. The metal box or casting not only furnishes bearings for the shafts, but also serves to protect the miter-wheels from becoming clogged with the grain, 40 which would occur if they were unprotected.

Having thus described my invention, what I claim, and desire to secure by Letters Patent of the United States, is—

1. The combination, with the hopper, of the 50 metal box secured upon the cross-beam in the same, the perpendicular shaft having the bent end or ends and curved transverse arms at either its lower or upper end, or at both, and having the central miter-wheel and the transverse shaft formed with the cranks, and having 55 the miter-wheel on its inner end, and means, substantially as described, for rotating the transverse shaft.

2. The combination, with the hopper, of the 60 perpendicular shaft having the miter-wheel on its central part and formed with the bent

end or ends, and provided with the curved transverse arms at either its lower or upper end, or at both, and the two transverse shafts formed with the cranks and having the miter-wheels at their inner ends, and means, substantially as set forth, for rotating one of the 65 said transverse shafts.

3. The combination, with the hopper, of the ribbed feed-roller having the pulley on the 70 outer end of its shaft, the metal box secured upon the cross-beam above the said feed-roller, the perpendicular shaft having the bent end or ends, and the curved transverse arms at either its lower or upper end, or at both, and 75 having the miter-wheel secured upon it at its center, the transverse shaft having the miter-wheel upon its inner end and the pulley on its outer end, and the drive-belts, substantially as set forth.

4. The combination, with a hopper, of the ribbed feed-roller having the pulley on the outer end of its shaft, the metal box secured upon the cross-beam above the said feed-roller, the perpendicular shaft having the bent end 80 or ends, and the curved transverse arms at either its lower or upper end, or at both, and having the central miter-wheel, the transverse shaft formed with the cranks and having the miter-wheel upon its inner end and the pulley 85 upon its outer end, and the drive-belts, substantially as and for the purpose set forth.

5. The combination, with the hopper, of the ribbed feed-roller having the pulley on the outer end of its shaft, the metal box secured 90 upon the cross-beam above the said feed-roller, the perpendicular shaft having the bent end or ends, and the curved transverse arms at either its lower or upper end, or at both, and having the central miter-wheel and the two 95 transverse shafts formed with the cranks, and having the miter-wheels upon their inner ends, the pulley upon the outer end of one of the 100 said transverse shafts, and the drive-belts, substantially as set forth.

6. The combination, with the hopper, of the ribbed feed-roller having the pulley on its shaft, the perpendicular shaft having the bent end or ends and the curved transverse arms at either its upper or lower end, or at both, and having the central miter-wheel, and the two 110 transverse shafts formed with the cranks and having the miter-wheels upon their inner ends, the pulley upon the outer end of one of the 115 said transverse shafts, and the drive-belts.

In testimony that I claim the foregoing as my own I have hereunto affixed my signature in presence of two witnesses.

SOLOMON M. GRAUMLICH.
